UNITED STATES PATENT OFFICE

ETTORE LANZEROTTI-SPINA, OF LONDON, ENGLAND

ROTARY ENGINE

Application filed October 26, 1928, Serial No. 402,761, and in Great Britain October 30, 1928.

This invention relates to rotary engines operating with fluids, that is to say rotary pumps or blowers and also motors, of the kind in which the volume of a cylinder is 5 swept by radial blades traversing and making joint with an eccentric drum or rotor.

Since the blade not only slides with respect to the drum but also tilts, the width of the narrow slot must be sufficient to allow for 10 maximum tilt; consequently when the blade is less tilted there will be clearance in the slot between the blade and the drum and means must be provided to make the joint. According to this invention I cause the blade in eff- 15 feet to expand resiliently and I lodge loose packing rods in grooves of larger section than the rods, formed in the edges of the drum slot. More specifically I use a rigid blade and provide it on one or both sides with a spring 20 blade set so that it normally tends to spring away from the rigid blade. I prefer to provide the spring blades on both sides since the clearance on both sides can then be taken up by a very light spring member irrespec- 25 tive of the variations in the position of the blade relative to the leading and trailing edges of the drum slot caused by inertia effects and the method of drive. The loose packing rods each have a flat side in contact 30 with the blade and are conveniently of seg- mental section. When the pump or the like is in action the rods are either thrown out- 35 wards by centrifugal force or driven inwards by pressure difference. In either case the flat side is urged against the blade and the other side makes contact with the surface of the groove thus sealing the joint. In designing 40 the engine the parts should be dimensioned so that the centrifugal force or the inward pressure predominates and a definite seal 45 obtained; it will be understood that in some cases, one force may preponderate during one part of the revolution and the other during the other part. I may also use the resili- 50 ent expansion of the blade or the loose pack- ing rods alone, the former being adapted for use with low pressures and the latter with high pressures. The described arrangements are suitable for use with liquid or gaseous

In the preferred form of the invention I employ a diametral blade in which case owing to the eccentricity of the rotor, the slot through which the blade passes on one side needs to move circumferentially relatively to 55 that on the other, and according to this invention I provide for such relative motion by using a rotor consisting of two concentric drums one fitting closely within the other; the blade traverses a narrow slot and makes joint 60 with one drum on one side, and the other drum on the other side, while each drum has a slot wide enough to allow for the described relative movement on the side opposite to the narrow slot. 65

Some embodiments of the invention are illustrated by way of example in the accompanying drawings in which

Figures 1 and 2 are cross sections of two 70 embodiments showing separately the two ar- rangements of packing respectively, and also the double drum.

Figures 3, 4 and 5 are longitudinal sections 75 of three different arrangements of engine. Figure 1 can be regarded as being taken on the line I—I of Figure 3, and Figure 2 as being taken as to the top right hand part on the line II—II of Figure 5 and as to the rest on the line II—II of Figure 4.

Figure 6 as to the left hand half is a de- 80 tail on an enlarged scale of Figure 2, and as to the right hand half a section showing the complete packing in use.

Figure 7 is a section as to the top right hand part on the line VII—VII of Figures 85 4 and 5 and as to the rest on the line VII—VII of Figure 3.

Figure 8 is a section on the line VIII—VIII of Figure 5.

Figure 9 is a sectional view of a valve 90 device whereby any of the engines when used as a pump may be caused to deliver in the same direction in whichever direction it is driven.

All the engines illustrated comprise a shaft 95 1 carrying a diametral blade 2 which passes through the shaft and sweeps the volume of a cylinder 3 coaxial with the shaft. The eccentric rotor comprises an inner drum 4 closely fitting over sufficient of its circum- 100

ference to make a tight joint, but movable within, an outer drum 5. The drums 4 and 5 have narrow slots respectively at 6 and 7 on opposite sides, and wide slots respectively at 8 and 9 on opposite sides to the narrow slots. As shown the drum makes contact with the cylinder over an arc 10 and the blade is therefore out of contact with cylinder during its traverse of the arc as at 11; accordingly the length of the arc 10 must be greater than the length of the slot 8 to prevent by-passing. Further, the thickness of the outer drum 5 must be sufficient to prevent the blade escaping entirely when in a position 180° to that shown in Figures 1 and 2. As shown in Figure 1, on each side of the rigid blade 2 is laid a thin spring blade 14 of identical shape to the rigid blade 2 and set so as to spring away from the blade 2 as seen at the bottom of the figure. In this way a tight joint between the blade and the drums at the slots 6, 7 is always maintained. The spring blades are conveniently of rolled spring steel and may be plated to resist corrosion.

As shown in Figures 2 and 6 the joint is made by a pair of flat faced segmental sectioned rods 15 which are lodged in axial grooves 16 in the drums 4, 5 with their flat faces bearing on the blade 2. These rods are here designed to be thrown outwardly and make joint with the blade and with the surfaces of the grooves.

Figure 6 also shows both systems of packing in use together. Here a spring blade 14 is used on each side of the rigid blade 2, but instead of making joint direct with the edges of the drum slots, as shown on the right hand side they bear against the flat faces of segmental sectioned rods 15 which are lodged in axial grooves 16 in the drums 4, 5.

In the engines illustrated, the output for a given size is increased by using the interior of the rotor. For this purpose the drum 4 is arranged to touch the shaft 1 and ports 17, 18 are provided in one or both end walls.

As shown in Figure 3 the engine may be arranged for the drive to be transmitted through any one of the three rotating members. In this figure the cylinder 3 is in one piece with one end wall 19, which is bushed at 20 to carry the shaft 1. The end wall is hollow and contains passages 44, 45 leading from the ports 17, 18 to the connections 21, 22 through openings 12, 13 as shown in Figure 7. The other end wall 23 is bolted on and bushed at 24 to carry a sleeve 25 made in one with the outer drum 5. This sleeve is bushed internally at 26 to carry a shaft 27 made in one with the inner drum 4. Thus the drive can be transmitted to the shaft 1, the sleeve 25 or the shaft 27 and those members not used can be cut off close and covered in. A further alternative is to drive the outer or the inner drum by providing

teeth on its periphery and providing a pinion meshing therewith.

The drums may be packed with soft material as at 28 and I prefer to carry the drums axially beyond the blade as at 29 to form complete rings so that the drums will not expand under centrifugal force and bind in the grooves in the end wall though this provision is more important in high speed pumps such as air blowers.

In Figure 4 there are two detachable end walls 30, 31 both of which are hollow and enclose passages 44 and 45 leading from the ports 17, 18 to the connections 21, 22 through the openings 12, 13. The drums 4, 5 are carried beyond the blade at both ends and there form complete rings and the shaft 1 is carried through both end walls.

A further construction intermediate between Figures 3 and 4 is possible in which the inner drum 4 has a shaft such as 27 in Figure 3 while the outer drum 5 is supported in grooves at both ends as in Figure 4.

In order to obtain the least fluctuation in flow, particularly when liquids are being dealt with, I prefer to drive through the shaft. To reduce fluctuations still further, I use a plurality of coaxial cylinders with common bearing members between each two adjacent cylinders, a common shaft, and common inlets and outlets. The drums and blades are arranged to produce the least possible fluctuation of flow. With all the drums concentric the blades will be set at the smallest possible angular intervals i. e.

180°/n where n is the number of cylinders. Such a construction is exemplified in Figure 5 which shows a double pump having its drums concentric and its blades 2a, 2b relatively at right angles so that at the instant when one is delivering at the maximum rate the other is delivering at the minimum rate and a substantially constant rate of flow is obtained. In the illustrated construction there are two coaxial cylinders 3a, 3b each in one with a hollow end wall 19a, 19b respectively provided as before with passages 44 and 45 and openings 12 and 13. The cylinders are bolted to a hollow centre section 32 which carries the connections 21, 22 which communicate through suitable passages with the ports 17, 18 and with the cylinder openings 12, 13. The shafts 1a, 1b are conveniently detachably coupled at the centre to permit assembly of the pump and I prefer to use an Oldham coupling 33 as this ensures that the blades are at a correct relative angle and allows identical shafts to be used. Alternatively a single shaft may be used by employing a constant diameter from end to end of the cylinders, or by using a collar in place of one of the enlarged bosses shown.

Where the pump is driven by a reversible engine and needs nevertheless to deliver in the same direction, I may provide a system

of valves to ensure this. The device shown in Figure 9 embodies such a valve system and can be applied to any of the pumps illustrated. The connections 21, 22 communicate respectively with chambers 34, 35 provided respectively with automatic inlet valves 36, 37 and automatic outlet valves 38, 39. The inlet valves open from a chamber 40 in which is provided the main inlet 41 and the outlet valves open into a chamber 42 provided with a main outlet 43. If now the pump rotates so that 21 is the suction branch, the fluid flows in at 41 through chamber 40, valves 35, and chamber 34, and flows out through connection 22, chamber 35, valve 39, chamber 42, and outlet 43. If the rotation of the pump is reversed, the flow is again in through 41 and chamber 40 and thence through valve 37, chamber 35, and connection 22, and the outflow is through connection 21, chamber 34, valve 38, chamber 42 and outlet 43.

What I claim is:—

1. A rotary engine for operation with fluids comprising a cylinder, a shaft concentric therewith, radial blades in said cylinder connected with said shaft, an eccentric rotor contacting with said cylinder having slots therein with grooved edges traversed by said blades, and loose radially movable packing rods of substantially smaller radial section than said grooves interposed between said blades and said grooves.

2. A rotary engine for operation with fluids comprising a cylinder, a shaft concentric therewith, radial blades in said cylinder connected with said shaft, an eccentric rotor contacting with said cylinder having slots therein traversed by said radial blades, and a spring blade on one side of each said radial blade and of substantially the same shape as said radial blade set to spring away from said radial blade.

3. A rotary engine for operation with fluids comprising a cylinder, a shaft concentric therewith, radial blades in said cylinder connected with said shaft, an eccentric rotor contacting with said cylinder having slots therein traversed by said radial blades, and a spring blade on each side of each said radial blade and of substantially the same shape as said radial blade set to spring away from said radial blade.

4. A rotary engine for operation with fluids comprising a cylinder, a shaft concentric therewith, radial blades in said cylinder connected with said shaft, an eccentric rotor contacting with said cylinder having slots therein with grooved edges traversed by said radial blades, a spring blade on each side of each said radial blade set to spring away from said radial blade, and loose rods of smaller section than said grooves interposed between said spring blades and said grooves.

5. In a rotary engine for operation with

fluids having a cylinder, radial blades and a slotted eccentric rotor traversed by said blades, means for packing the joints between said blades and said rotor comprising loose radially movable segmental sectioned rods located in curved section grooves in the edges of the rotor slots of substantially larger radius than the section of said rods.

6. A rotary engine comprising a cylinder, a shaft concentric therewith, a diametral blade, a spring blade of identical shape on each side of said diametral blade set to spring away therefrom, said three blades being carried in a slot in said shaft, and an eccentric rotor making contact with said cylinder and said shaft and twice traversed by said blades.

7. A rotary engine for operation with fluids comprising a cylinder, a shaft concentric therewith, radial blades in said cylinder connected with said shaft, an eccentric rotor contacting with said cylinder having slots therein with grooved edges traversed by said radial blades, a spring blade on one side of each said radial blade set to spring away from said radial blade, and loose rods of smaller section than said grooves interposed in said grooves.

8. In a rotary engine comprising a central bearing member, a pair of coaxial cylinders one secured on each side of said central member, an eccentric rotor in each said cylinder, and a diametral blade in each said cylinder traversing the rotor therein, said blades being at right angles to one another, the combination of a shaft in each said cylinder operatively connected with the corresponding blade and projecting into said central bearing member and an Oldham coupling in said central bearing member connecting said shafts.

9. A rotary engine for operation with fluids comprising a cylinder, a shaft concentric therewith, a radial blade connected with said shaft, an eccentric rotor contacting with said cylinder having a slot with grooved edges traversed by said blade, and loose radially movable packing rods of substantially smaller section than said grooves interposed between said blade and said grooves.

10. A rotary engine for operation with fluids comprising a cylinder, a shaft concentric therewith, a radial blade in said cylinder connected with said shaft, an eccentric rotor contacting with said cylinder having slots therein traversed by said radial blade, and a spring blade on one side of said radial blade and of substantially the same shape as said radial blade set to spring away from said radial blade.

In testimony whereof I have signed my name to this specification.

ETTORE LANZEROTTI-SPINA.
